A. H. MOE

CIGARETTE AND MATCH HOLDER

Filed March 19, 1926

INVENTOR:
Albert H. Moe
BY David E. Carlson
ATTORNEY.

Patented Oct. 26, 1926.

UNITED STATES PATENT OFFICE.

ALBERT H. MOE, OF ST. PAUL, MINNESOTA.

CIGARETTE AND MATCH HOLDER.

Application filed March 19, 1926. Serial No. 95,867.

My invention relates to an improved combination holder for cigarettes and matches and the object is to provide a simple, inexpensive, highly efficient and convenient device in which cigarettes may be kept in their original packages or held loosely within the device and also a match-box holder, the device being so arranged that cigarettes and matches are available simultaneously. These and other objects will be brought forth in the following specification and as fully illustrated in the accompanying drawing in which;

Fig. 1 is a top view of my device.

Fig. 2 is a front view of my device with its lid opened to expose the cigarettes in its upper compartment and a match-box in the lower compartment, the drawer of the match-box partly out.

Fig. 3 is a left hand edge view of Fig. 2.

Fig. 4 is a bottom view of the device.

Fig. 5 is a longitudinal section of the holder about as on line 5-5 in Fig. 3.

Fig. 6 is a sectional elevation through the match-box compartment about as on line 6-6 in Fig. 5.

Fig. 7 is a modification of Fig. 5 and showing a package of cigarettes and a matchbox in their respective compartments.

Referring to the drawing by reference numerals, my holding device comprises a preferably sheet metal box 10 of elongated quadrangular form, with a suitable hinged lid 11 for closing the larger compartment

12 of two compartments 12-13. The device is preferably of elongated flat shape similar to a tobacco can and of a size to receive and retain an entire package of cigarettes 14 in the larger compartment in such a manner that when the wrapper of the upper end of such package is torn away the ends of the cigarettes project above the top edge of the box and are readily accessible when the lid 11 is turned up as in Fig. 2. The lid 11 is

necessarily deep enough to protect but not contact with the cigarettes, when closed, and may be retained in closed position by any suitable means such as a projection 15 of the metal in the front upper part of the box and frictionally engaged by a corresponding dentation 16 on the cover.

For convenience of description I will designate the front wall, rear wall, right and left edges of the container 10, as A, B, C and D respectively.

The compartment 12 may have a solid bot-

tom as 17 in Fig. 7 for supporting the bottom end of a cigarette package, or cigarettes may in this instance be placed loosely and upright in the compartment. 18 are inwardly directed spring arms or integral parts of the edge walls D and C, one extending downwardly from the top edge of each said walls angularly toward the center of the compartment. These arms serve as retaining means for a package of cigarettes slipped downwardly into the compartment, as 14 in Fig. 7. Below the partition 17 the box edge C has an opening 19 through which an entire match-box 20 of the usual small size may be slipped into compartment 13 until its inner end stops against wall D. In Figs. 2, 6 and 7 the said match-box is shown with the usual shell 20^A and drawer 20^B. This shell 20^A is frictionally retained in the compartment 13 by a flat spring arm 21 preferably consisting of a continuation of rear wall B bent back at B' and extending inwardly toward wall D and upwardly toward wall A. A match-box 20 inserted as in Fig. 6 will of course be frictionally retained between said arm 21 and wall A. 22 (Figs. 3 and 7) is an aperture in the lower part of wall D and large enough for the user of the device to insert a finger, as 23 in Fig. 7, to push one end of the match-box drawer and force the latter out as far as desired from wall C to provide easy access to the matches 24.

In Figs. 5 and 6 the upper edge of spring arm 21 is formed with horizontal, alternating projections or lips 21^L in a common plane and being located below the free ends of the arms 18 serve as the supporting element for the bottom of the cigarette package. In this type of holder the solid bottom 17 is omitted. In Fig. 6 the bottom end of the cigarette package 14 is indicated dotted.

The lower end of my device may be made in very light construction with the metal simply bent under to form the quadrangularly arranged ledges 25 (see Fig. 4).

The use of my device is already clearly revealed. It is obvious that the arms 18 and 21 may readily be cut from the same blank of sheet metal as the box itself. These arms may also be of spring material suitably fixed in the box but these and other expedients fall within the intended scope and spirit of the invention.

What I claim is:-

1. A cigarette and match-box holder comprising an elongated, quadrangular, tubular body, a hinged lid adapted to close one end, said body having two compartments, one for cigarettes and the like and accessible when the lid is opened, a smaller compartment at the opposite end of the holder, the latter having an opening in its edge for insertion of a match-box and a smaller opening in the edge opposite from the one in which a match-box is inserted, and means within both compartments for frictionally retaining a package in the larger compartment and a match-box in the smaller compartment, said retaining means consisting of a number of spring arms in each compartment.

ment, each of said arms extending normally from the vicinity of the opening of its compartment and angularly into the compartment.

2. The structure specified in claim 1, in which said spring arm in the smaller compartment comprises a flat spring with one edge arranged transversely and nearly across the interior of the holder and said edge having integral ledges arranged in a common plane at right angles to the plane of the spring to serve as a supporting element for the bottom of a package inserted in the larger compartment.

In testimony whereof I affix my signature.

ALBERT H. MOE.
